UNITED STATES PATENT OFFICE.

HARRY E. DAWE, OF PERTH AMBOY, NEW JERSEY.

WASHBOARD-SUPPORT.

1,211,298.

Specification of Letters Patent. Patented Jan. 2, 1917.

Application filed August 30, 1916. Serial No. 117,695.

To all whom it may concern:

Be it known that I, HARRY E. DAWE, a citizen of the United States, residing at Perth Amboy, in the county of Middlesex and State of New Jersey, have invented new and useful Improvements in Washboard-Supports, of which the following is a specification.

This invention relates to wash boards which are particularly designed for use in connection with a stationary wash tub, the primary object of the invention being to provide a device of this character which is simple, efficient and durable in construction.

The special object of this invention is to provide an improved supporting means for the wash board to rigidly support the washboard in active position within the tub, the supporting means being so constructed as to permit the ready removal of the board when not in use.

Details will appear as the specification is read in connection with the accompanying drawings, in which:—

Figure 1 is a front elevation of the wash board showing the stationary tub in section. Fig. 2 is an edge elevation of the wash board, the tub being shown in section. Fig. 3 is an enlarged detailed vertical section of the supporting means and wash board, the same being taken on the line 3—3 of Fig. 1.

Referring to the drawings in detail, A designates a stationary wash tub of the usual construction which is provided with an inclined side wall 1, and the ledge 2 which is secured to the upper edge of the tub in such a manner as to cause the inner edge to project beyond the inner surface of the inclined wall 1, as is clearly illustrated in Figs. 2 and 3.

Secured to the inner edge of the ledge 2 and extending longitudinally of the same is a metal strip 3 which is provided adjacent its opposite ends with sockets 4. The sockets 4 are in this instance of rectangular formation and have their outer side face provided with longitudinally extending slots 5 while, arranged upon the inner face of the outer side of each of the sockets, and projecting rearwardly therefrom, is a longitudinally extending projection or lug 6, which is disposed above the slot 5 as is clearly shown in Fig. 3 of the drawings.

My improved form of wash board, which is generally indicated as at B, comprises a single sheet of metal or other suitable ma-

terial which is of rectangular formation and which has the edge thereof provided with a depending flange 7, the flange being tapered in width from the lower end of the wash board to the upper end thereof as is clearly shown in Fig. 3. The body portion of the wash board is corrugated as at 8 for a major portion of its width, the corrugations terminating short of the upper edge of the board, the uppermost corrugation being relatively larger than the remaining corrugations to provide a shelf or soap rest 9. Secured to the face of the wash board adjacent the upper end thereof are the supporting members 10 which are in this instance formed of stiff metal strips which are secured to the wash board by means of rivets 11. The supporting members 10 are arranged adjacent the opposite ends of the wash board and are of such a length as to extend an appreciable distance beyond the upper edge of the wash board, the free ends of the supporting members terminating in angularly disposed L-shaped extensions 12.

In practice, the wash board is supported in suspension, within the stationary tub and upon the inclined wall 1, by inserting the L-shaped extensions through the slots 5 and into the sockets 4 by holding the wash board in inverted vertical position whereby the tips of the extensions 12 will be so positioned as to permit the ready insertion thereof into the slots. The extensions having been inserted, the wash board may now be swung downwardly within the tub so as to assume the position as shown in all of the figures of the drawing, the free edge of the flange 7 engaging the inner face of the inclined wall 1 at a time when the tips of the extensions come in contact with the lugs 6, and such contact prevents the hooked extensions from disengaging the slots 5 accidentally. It will thus be seen that the wash board may be suspended in rigid position within the tub and that the wash board will be held securely against downward or horizontal movement within the tub, so that the operator may conveniently wash the clothes.

When it is desired to remove the wash board, by swinging the lower end of the board upwardly so as to cause the board to assume an inverted position the extensions 12 may then be readily withdrawn from the sockets 4, the tapered flange 7 being particularly designed for the purpose of permitting the upper part of the washboard to move

rearwardly or in a direction toward the inclined side wall when disengaging the extensions from the sockets.

It is thought from the foregoing taken in connection with the accompanying drawings that the construction and operation of this device will be apparent to those skilled in the art without further description, and that minor changes in size, shape, proportion and minor details of construction may be made without departing from the spirit and scope of the appended claim.

What I claim is:

The herein described device for supporting wash boards within a tub, the same comprising a strip adapted for attachment with-

in the front wall of the tub and having on it a plurality of sockets, each of the same being hollow and provided with a slot in its front face near its lower edge and an internal lug above said slot, and a plurality of metallic strips adapted for attachment to the washboard at points corresponding with the position of said sockets, each strip projecting above the upper edge of the board and having its projecting portion bent into an L-shaped extension whose tip is adapted to rest against the lug when its shank passes through the slot of one of such socket members, for the purpose set forth.
